UNITED STATES PATENT OFFICE.

LEWIS HARE, OF CUSTER, SOUTH DAKOTA.

DESIGN FOR AN INSTEP-STIFFENER.

SPECIFICATION forming part of Design No. 28,800, dated June 7, 1898.

Application filed January 21, 1898. Serial No. 667,496. Term of patent 14 years.

To all whom it may concern:

Be it known that I, LEWIS HARE, a citizen of the United States, residing at Custer city, in the county of Custer and State of South Dakota, have invented and produced a new and original Design for an Instep-Stiffener; and I do declare the following to be a full, clear, and exact description of the same, reference being had to the accompanying drawings and specification, forming a part thereof.

Figure 1 is a side elevation of my invention. Fig. 2 is a perspective view of my invention. Fig. 3 is a rear view of my invention.

The leading or material feature of my design consists of a flat perforated plate having an L-brace flat on its bottom, its front face curved backward, its rear face straight, and having a rear perforated extension flush with the bottom of said brace, and rearwardly-extending points flush with the upper face of the plate.

1 represents a flat piece of material—a shank-plate—which covers the shank and is

provided with perforations 2. Integral with this shank-plate is the heel-brace 3, flat on its bottom and having extending from the rear part of its bottom and flush with the face thereof an extension 4, provided with perforations 5. Extending rearwardly from the upper face of the heel-brace 3 are two points 8. The front face of the heel-brace 3 is bowed backward, as shown, and in the rear face of the said heel-brace are two grooves 9, and running through the said heel attachment 35 is a screw-hole 10.

Having described my invention, what I claim as new, and desire to obtain by Letters Patent, is—

The design for an instep-stiffener, as herein shown and described.

In testimony whereof I affix my signature in presence of two witnesses.

LEWIS HARE.
